UNITED STATES PATENT OFFICE.

JANET PEARL, OF MOUNT BEACON, NEW YORK, ASSIGNOR TO BERNHARD ULMANN CO., INC., OF NEW YORK, N. Y., A CORPORATION OF NEW YORK.

DESIGN FOR A CROCHETED OR KNITTED WRAP.

52,855.

Specification for Design.

Patented Jan. 7, 1919.

Application filed May 26, 1917. Serial No. 171,332. Term of patent 3½ years.

To all whom it may concern:

Be it known that I, JANET PEARL, a citizen of the United States of America, and a resident of Mount Beacon, county of Dutchess, and State of New York, have invented a new, original, and ornamental Design for a Crocheted or Knitted Wrap, of which the following is a specification, reference being had to the accompanying drawings, showing my design.

Fig. 2 shows a perspective side view of the wrap as it appears when worn.

I want it understood that my claim includes all substantial equivalents of the design as shown.

I claim:

The design for a crocheted or knitted wrap substantially as shown.

JANET PEARL.
